(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view of FIG. 1, showing the electronic device where a graphical user interface is displayed.

The dashed broken lines showing portions of a graphical user interface in FIG. 8 are for the purpose of illustrating environment and form no part of the claimed design. The remaining dashed broken lines in the figures illustrate portions of the electronic device that form no part of the claimed design. The dot-dash broken lines in the figures define the boundaries of the claimed design and form no part thereof.
